UNITED STATES PATENT OFFICE.

WILLIAM WYNKOOP WATKINS, OF YUMA, ARIZONA TERRITORY.

ROTARY ENGINE.

SPECIFICATION forming part of Letters Patent No. 650,286, dated May 22, 1900.

Application filed January 18, 1898. Serial No. 667,106. (No model.)

To all whom it may concern:

Be it known that I, WILLIAM WYNKOOP WATKINS, residing near Yuma, in the county of Yuma and Territory of Arizona, have invented a new and useful Improvement in Rotary Engines, of which the following is a specification.

My invention is an improvement in the class of reversible rotary engines in which steam or other motive fluid is allowed to impinge upon the periphery of a circular wheel adapted to rotate within a suitable casing.

The invention is embodied in the construction and combination of parts, as hereinafter specified.

In the accompanying drawings, Figure 1 is a side view of my invention. Fig. 2 is a vertical central longitudinal section of the same. Fig. 3 is a central transverse section showing the arrangement of the valve and steam conduits or pipes. Fig. 4 is a detail plan view showing the arrangement of the steam conduits or pipes.

The wheel proper (see Fig. 2) is a thick circular disk having a series of equidistant peripheral cups or pockets 2, which form recipients for the steam or other fluid used as a motive agent. This wheel 1 is mounted upon a horizontal shaft 3, that passes through and has its bearings in a casing 4, whose inner sides are parallel and close to the wheel, as shown in Fig. 2, and are extended upward at 5 to form a conduit for exhaust or waste steam. The shaft 3 is coupled with two alined shafts 6 by means of clutch-disks 7. On the outer ends of said shafts 6 are keyed sprocket-wheels 8, upon which chains (not shown) may run for driving some form of machinery. The shafts 6 are mounted in bearings 9, having antifriction-balls 10, and provided with openings for admitting a lubricant.

Steam is admitted to the casing and discharged upon the wheel 1 by means of a pipe 11, Fig. 3, having two branches 12 12', which extend a short distance around the periphery of the wheel and whose free ends open in close proximity to the same. Other branches 13 and 13' diverge laterally from the primary branches 12 and 12' and extend still farther around the wheel 1, the same opening at their free ends in line with the periphery of said

wheel, as shown in Figs. 2, 3, and 4. It will be seen that steam may thus be delivered or caused to impinge on the wheel 1 at opposite points—that is to say, at two points on the upper and lower sides.

For controlling admission of steam I employ the two-way rotary valve 14, Fig. 3, which is arranged at the junction of pipe 11 and its primary branches 12 and 12'. As shown, said valve is adapted to shut off admission of steam to the lower branches 12' and 13' and permit its passage to and through the upper ones, 12 and 13, and thus upon the upper side of the wheel 1, whereby the latter is driven to the left or in the direction indicated by arrows, Fig. 3. It is obvious that by reversing the valve 14 or rotating it more than half-way around the upper pipe branches 12 and 13 will be closed and the lower ones, 12' and 13', opened, so that the rotation of the wheel will be reversed. The nozzle or discharge end of each of the four steam pipes or conduits is in such local relation to the wheel 1 as to discharge steam into the cups 2, and the latter being narrower at their outer ends or mouths than their middle they catch and hold the steam momentarily, so that a maximum propulsive effect is produced without hindrance to free release or escape of the steam.

The means for rotating the valve 14 are the following: The shaft 15 projects laterally through the casing 4 and is held in suitable bearings. A hand-lever 17 is affixed to an internally-toothed gear 18, which incloses and meshes with a pinion 19, keyed on a stub-shaft 15, having its bearings in the side of the casing 4 and carrying the valve 14, which is keyed on its inner end. The said gear 18 has radiating arms, and its hub is keyed on a shaft having bearings 16, forming part of a pedestal or vertical support 16'. The said lever 17 is provided with a spring-pawl 20, that has a locking engagement with the rack-bar 21.

What I claim is—

The improved rotary engine, comprising the rotary wheel having peripheral cups, the casing 4 having spaces formed in extensions thereof above and below said wheel, the main steam-conduit 11, the two short, oppositely-

diverging pipes 12 and 12', and the longer pipes 13 and 13', opening out of and diverging laterally from said shorter pipes, and extending forward around the wheel, all the said 5 pipes having their nozzles or mouths in line with and in close proximity to the periphery of the wheel, and the rotary valve 14, arranged

at the junction of the shorter pipes, as shown and described.

WILLIAM WYNKOOP WATKINS.
